UNITED STATES PATENT OFFICE

2,603,969

ART OF EVALUATING SANITARY PAPER PRODUCTS

John T. Sobota, Green Bay, Wis., assignor to Fort Howard Paper Company, Green Bay, Wis., a corporation of Wisconsin

Application October 5, 1949, Serial No. 119,629

2 Claims. (Cl. 73—159)

1

This invention relates to improvements in the art of evaluating sanitary paper products.

One of the qualities of sanitary paper products such as toilet paper, paper towels, napkins, facial tissue and the like which is judged most critically by a prospective purchaser, is absorbency and absorbency is particularly important in the case of toilet paper where, if this quality is not present, a plugged toilet is likely to result. In view of the fact that the quality of absorbency influences sales, it is desirable to be able to perform tests in front of the prospective purchaser. Heretofore, tests for absorbency have necessitated the use of complicated apparatus in a laboratory and, in most instances, it is necessary to be an expert in order to evaluate the results of the test.

It is a general object of the present invention to provide an improved method of evaluating sanitary paper products which can be performed quickly and easily in any location, and which can be readily understood by anyone watching the test.

A further object of the invention is to provide improved apparatus for carrying out the method, the said apparatus being in easily portable form so that it may be carried from one location to another and operated before a prospective buyer.

A further object of the invention is to provide an improved method and apparatus which permits the ready comparison of different brands or grades.

A further object of the invention is to provide improved method and apparatus by means of which the rate of disintegration of paper products may be determined and expressed numerically in terms of the number of shaking strokes necessary to produce a predetermined degree of disintegration.

With the above and other objects in view, the invention consists of the improvements in the art of evaluating sanitary paper products, and all its parts and combinations, as set forth in the claims, and all equivalents thereof.

In the accompanying drawings, illustrating the preferred form of apparatus which may be employed to carry out the improved method:

Fig. 1 is a perspective view, principally in side elevation showing the improved apparatus with a liquid container supported thereon;

Fig. 2 is a perspective view looking principally at the opposite side of the apparatus from Fig. 1 with the liquid container removed; and

Fig. 3 is an elevational view of the container alone showing it in liquid discharge position, parts being broken away and shown in vertical section.

2

Referring more particularly to the drawing, the numeral 5 designates a suitable base having mounted thereon an electric motor 6. Through suitable reduction gearing in a gear box 7 the motor drives a shaft 8, and the latter has rigidly mounted thereon a disc or wheel 9. Eccentrically located on the disc or wheel 9 is a pin or crank 10 which operates a pitman 11, the latter being pivotally connected as at 12 to an oscillatory arm 13 at a point intermediate the length of said arm. The lower end of the arm 13 is pivoted as at 14 to a bracket 14' on the base 5. The upper end of the arm 13 carries a cradle 24 for removably supporting a container 15 on its side, as in Fig. 1. The cradle 24 may be of any form to suit the particular shape of the container. Where a bottle of the type illustrated in Fig. 1 is employed, the cradle may include a longitudinal member 16 having an angularly bent end 17 for engagement with the bottom of the bottle and having its opposite end curved as at 18 for engagement with the curved forward portion of the bottle. The cradle may also include spaced semi-circular bands 19 which are secured to the member 16 and which extend transversely thereof.

The preferred form of apparatus also includes a counter 20 of any well known form having an operating arm 21. A link 22 has one end pivoted as at 23 to the operating arm 21 of the counter and has its other end pivotally connected to the crank pin 10. While the use of a counter is preferred because it makes the test more convincing, it is, nevertheless, possible to perform an effective demonstration without a counter.

The container 15 has a discharge opening 25 formed in its neck 26. It is also preferably equipped with a vent hole 27 which may be removably closed by a stopper 28.

To make the most effective type of demonstration it is preferred to have a trap-simulating attachment 29 for the bottle, which attachment has one end equipped with a rubber adapter 30 insertible into the opening 25 of the bottle, the other end of the trap simulating device being open as at 31. While the device 29 is shown with a double bend, only one bend may be used if desired.

In its broadest aspects, the improved method is carried out as follows: The bottle or container 15 is filled approximately half full of water at room temperature. There is then inserted into the bottle a predetermined quantity of the paper to be tested. In the case of toilet paper it is preferred to insert three sheets of $4\frac{1}{2} \times 4\frac{1}{2}$ paper

or the equivalent. The bottle is then closed by a stopper or cover 32 and shaken a predetermined number of times. It is then opened and inverted. In the case of toilet paper, if it has been shaken 125 times, a good grade of toilet paper should flow freely through the neck and out of the bottle. During the test the transparent container enables one to observe the behavior of the paper so that absorbency or lack of absorbency can be readily noticed. Generally, an absorbent paper will wet quickly and settle in the bottle.

In order to make the test more realistic, it is preferred to employ some form of trap-simulating device, such as the member 29, when the bottle is inverted after it has been shaken. A good grade of paper should flow freely out of the open end 31 of the trap 29. However, when a trap is employed it is generally necessary to vent the bottle by removing the stopper 28.

The apparatus illustrated and heretofore described makes it possible to carry out the method easily and quickly, and makes accurate comparisons of several brands of paper possible. When using the improved apparatus, the motor 6 is operated until the counter 20 registers on its dial 33 a predetermined number of shaking strokes. Thus, if the apparatus is used to compare competitive brands, the buyer can tell from the counter that each brand has been shaken the same number of times.

The apparatus illustrated can be made in relatively small, compact form to fit a relatively small salesman's case. Thus the outfit may be taken along on sales trips as an aid when interviewing prospective buyers.

The improved method and apparatus make it possible to express the rate of disintegration of paper numerically in terms of the number of strokes necessary to disintegrate the paper to such a degree that the paper and water will flow freely from the bottle when inverted.

In the preferred embodiment of the invention which is particularly designed for the handling of three sheets of 4½ x 4½ toilet paper, the speed of the motor reducer is 160 R. P. M. and the capacity of the container is such that when it is half full it contains 125 cc. of water.

Various changes and modifications may be made without departing from the spirit of the invention, and all of such changes are contem-

plated as may come within the scope of the claims.

What I claim is:

1. A method of evaluating sanitary paper or the like comprising: inserting a predetermined quantity of completely formed paper in a body of liquid, shaking the paper and liquid together in a predetermined manner a predetermined number of times while confined to provide a mixture, then causing the mixture of paper and liquid to flow under the influence of gravity, and guiding the flow of the mixture through an elongated path which extends first in one direction and then in a generally reverse direction while at the same time confining it within predetermined maximum limits, which limits permit passage of said mixture if formed from paper having a predetermined standard rate of disintegration and resist passage of said mixture if formed from paper having less than said predetermined standard rate of disintegration.

2. A method of evaluating sanitary paper or the like comprising: inserting a predetermined quantity of completely formed paper in a body of liquid, shaking the paper and liquid together in a predetermined manner a predetermined number of times while confined to provide a mixture, then causing the mixture of paper and liquid to flow under the influence of gravity while guiding and confining it within predetermined maximum limits, which limits permit passage of said mixture if formed from paper having a predetermined standard rate of disintegration and resist passage of said mixture if formed from paper having less than said predetermined standard rate of disintegration.
